J. I. MISENER & W. S. SANDERS,
METAL CUTTING TOOL,
APPLICATION FILED OCT. 11, 1917.

1,281,627.

Patented Oct. 15, 1918.

UNITED STATES PATENT OFFICE.

JOHN I. MISENER AND WILLIAM S. SANDERS, OF SYRACUSE, NEW YORK; SAID MISENER
ASSIGNOR, BY DIRECT AND MESNE ASSIGNMENTS, TO MISENER & IRVING MANU-
FACTURING CO. INC., OF SYRACUSE, NEW YORK, A CORPORATION OF NEW YORK.

METAL-CUTTING TOOL.

1,281,627.

Specification of Letters Patent. Patented Oct. 15, 1918.

Application filed October 11, 1917. Serial No. 196,042.

To all whom it may concern:

Be it known that we, JOHN I. MISENER and WILLIAM S. SANDERS, of Syracuse, in the county of Onondaga and State of New York, have invented a certain new and useful Metal-Cutting Tool, of which the following is a specification.

This metal cutting tool is an improved construction of the pending application of Misener, Skroback and Sanders, Serial No. 148,973 filed February 16, 1917, and has for its object a particularly simple and efficient attachment therefor, whereby the range of said metal cutting tool is increased. It also provides for a universal movement between the body and the spindle of said tool and includes a simple and efficient means for locking said universal movement.

In describing this invention, reference is had to the accompanying drawing in which like characters designate corresponding parts in all of the views.

Figure 1 is a sectional view partly in elevation of this metal cutting tool.

Fig. 2 is an inverted face view of the same, partly in section.

Fig. 3 is a sectional view partly in elevation of parts seen in Fig. 1, taken at a right angle thereto.

Fig. 4 is a plan view of the spindle; and Fig. 5 is a section on line 5—5, Fig. 1, looking down, parts being removed.

This invention comprises generally a rotating head having a flat face with circular grooves therein, concentric with the axis of rotation of the head, an arc-shaped hacksaw held in one of said grooves having means at the forward end thereof for holding the same from rotative movement relatively to said head, a spindle extending from the head, means for obtaining a universal movement between the rotary head and said spindle, means for locking said parts from universal movement, means extending axially from the head for forming a central bearing therefor and means for attaching an additional groove containing part to said head.

This tool is particularly adapted for use with a hand-operated device, as a hand drill or the like, but obviously is just as efficient when used with power operating machines.

1 is the rotary head which is here shown as circular and is provided with a flat face 2 disposed at a right angle to the axis of 55 rotation of said head. 3 are circular grooves forming in the flat face 2, concentric with the axis of rotation of the head 1.

The cutting edge comprises a flat hacksaw or metal saw 4, formed in an arc with 60 the usual teeth 5 set, as customary with saws of this character.

In Figs. 1 and 2 of the drawing, we have shown a particularly simple and efficient attachment for this tool, by the use of which 65 we are enabled to increase the range of said tool and cut holes of any desired size.

6 is the body of said attachment which in this embodiment of our invention is in the form of a ring having a flat face 7 with 70 grooves 8 therein, corresponding to the face 2 and grooves 3 of the rotary head 1.

The outer side 9 of the rotary head closely fits the inner diameter 10 of the ring 6 and the upper part thereof is formed with an 75 annular extension 11 which fits into a complementary annular recess 12 formed in the ring 6. The head is formed with projections or lugs 13 and the ring with open ended slots 14 forming bayonet joints for locking 80 said parts.

In use the lugs 13 of the rotary head 1 are placed in the open ends of the slots 14 of the attachment or ring 6 thereby bringing the extension 11 of the head into the recess 12 formed in the ring. A slight turn of the head forces the lugs into the end of the slots 14 thereby locking the bayonet joint and holding the head and ring together.

The extension 11 fits into the recess 12 and releases the lugs 13 from strain when pressure is applied to the head.

Obviously, the attachment or ring may be provided with an extension and lugs similar to those of the rotary head for locking additional rings thereto, or each ring may be provided with but a single groove of the desired diameter.

In use the saw blade is sprung into one 100 of the concentric grooves and is held from movement relatively to the rotation thereof by means of a pin 15 extending radially into the head 1, or through the attachment 6,

from the outer diameter thereof and passing through the grooves and through one end of the saw blade 4, there being one pin 15 for the head and one for each attaching ring.

As the grooves are made wide enough to readily receive the saw, the saw conforms or hugs one of the sides as the inner side of the groove and in order to permit the saw

10 to so conform to one of the circular walls of the groove without distortion or buckling, the saw is secured in position to the head at one point only as at the advance end thereof with respect to the direction of rotation.

15 The wall of the groove which the saw engages during the use thereof is approximately the diameter of the hole to be cut.

The rotary head 1 is provided with means for forming a central bearing for the tool

20 and as here shown, a passage 16 is formed axially therein extending from the flat face 2 thereof. A drill 17 is held in said passage 16 by a set screw 18, and the cutting surface of the drill extends beyond the flat face of 25 the head 1 and beyond the teeth 5 of the arc-shaped cutting edges.

As the cutting edge of this tool extends around the greater part of the circumference of the hole to be cut, thus presenting 30 a large cutting surface to the work, it is desirable that equal pressure be exerted on the entire cutting surface, in order that the tool will cut with most efficiency. To accomplish this, we have provided our tool with a universal joint between the rotating head and the spindle from which the power is transmitted.

As here shown, the head 1 is provided with an upwardly extending hub 19 having

40 a cup-shaped socket 20 in its upper end. The spindle 21 is squared at its lower end, as shown at 22, extends into a socket 23 of a ball-shaped member 24 and is pivoted by a pin 25 thereto, the socket 23 being of sufficient length to allow the spindle to pivot 45 therein. The ball-shaped member is provided with an external rib 26 extending around the lower half thereof on a plane of the pivot 25 and the cup-shaped socket

50 is provided with a complementary groove 27. A cap 28 provided with a square opening 29 in the top thereof is threaded on the hub 19 to hold the ball-shaped member in its socket 20.

55 The surfaces 30 at the meeting edges of the squared part 22 of the spindle are of the same diameter as the distance diametrically between squared sides of hole 29 in the cap 28, and as clearly illustrated in Fig. 60 5 of the drawing, an eighth of a turn of the cap 28 will lock the head 1 and the spindle 21 from universal movement.

The spindle 21 is tapered and is provided with flat sides 31 for clamping the same in 65 the jaws of a hand drill or brace, and the

extreme end of the spindle on two of the flat sides is cut away, as at 32, for entering the socket in the chuck of a power machine.

In use the operator first locates the center where the hole is to be cut and places the 70 point of the drill thereon; upon rotation of the head, the drill cuts a small hole in the metal, which hole centers the cutting edge with respect to the hole to be cut and forms a central bearing for the tool.

Upon further rotation of the head 1 the teeth of the cutting edge come in contact with the surface to be cut and as it presents a large cutting face to said surface, cuts through the same very rapidly.

What we claim is:

1. A metal cutting tool comprising a rotary head for holding a cutting edge, a spindle extending therefrom for connection with a rotating means, means for obtaining 85 a universal movement between the rotary head and said spindle, and means for locking said parts from universal movement, substantially as and for the purpose specified.

2. A metal cutting tool comprising a rotary head, having a flat face with a circular groove therein concentric with the axis of rotation thereof, an arc-shaped hacksaw in said groove with the cutting edge thereof 95 extending beyond and parallel with the flat face of the rotary head, the saw having means at one end thereof for holding the same from rotative movement relatively to said head, a spindle extending from the 100 head and means for obtaining a universal movement between the rotary head and said spindle, substantially as and for the purpose set forth.

3. A metal cutting tool comprising a rotary head having a flat face with circular grooves therein concentric with the axis of rotation thereof, an arc-shaped hacksaw in said groove with the cutting edge thereof 110 extending beyond and parallel with the flat face of the rotary head, the saw having means at one end thereof for holding the same from rotative movement relatively to said head, a spindle extending from the head, means for obtaining a universal movement 115 between the rotary head and said spindle and means for locking said parts from universal movement, substantially as and for the purpose described.

4. A metal cutting tool comprising a rotary head having a flat face with a circular groove therein concentric with the axis of rotation thereof for holding an arc-shaped hacksaw, and means for removably attaching an additional groove containing part to 125 said rotary head, substantially as and for the purpose specified.

5. A metal cutting tool comprising a rotary head having a flat face with a circular groove therein concentric with the axis of 130

rotation thereof, an arc-shaped hacksaw in said groove with the cutting edge thereof extending beyond and parallel with the flat face of the rotary head, the saw having 5 means at one end thereof for holding the same from rotative movement relatively to said head, a spindle extending from the head and means between the rotary head and the spindle for equalizing the pressure 10 on said arc-shaped hacksaw, substantially as and for the purpose described.

In testimony whereof, we have hereunto signed our names in the presence of two attesting witnesses, at Syracuse, in the county of Onondaga and State of New York, this 15 28th day of Sept., 1917.

Correction in Letters Patent No. 1,281,627.

It is hereby certified that Letters Patent No. 1,281,627, granted October 15, 1918, upon the application of John I. Misener and William S. Sanders, of Syracuse, New York, for an improvement in "Metal-Cutting Tools," were erroneously issued to Misener & Irving Manufacturing Co. Inc., as assignee, and the second-named inventor, said Sanders, jointly, whereas said Letters Patent should have been issued to *Misener & Irving Manufacturing Co. Inc.*, as assignee of the *entire interest* in said invention, as shown by the records of assignments in this office; and that the said Letters Patent should be read with this correction therein that the same may conform to the record of the case in the Patent Office.

Signed and sealed this 10th day of December, A. D., 1918.

[SEAL.]

F. W. H. CLAY,

Acting Commissioner of Patents.
